(57) **CLAIM**

The ornamental design for a flowerpot, as shown and described.

DESCRIPTION

FIG. 1 is a top view of a flowerpot showing my new design.
 FIG. 2 is an upper perspective view thereof;
 FIG. 3 is a lower perspective view thereof;
 FIG. 4 is a front view thereof, wherein rear, right side and left side views are identical; and,
 FIG. 5 is a bottom view thereof.

The broken lines in FIGS. 3 and 5 illustrate portions of the flowerpot that form no part of the claimed design.
